DEVICE FOR DETERMINING AZIMUTH BY
OBSERVATIONS ON POLARISStephan Guttormsson, Winnipeg, Manitoba,
CanadaApplication March 23, 1933, Serial No. 662,280,
and in Canada March 2, 1933

1 Claim. (Cl. 33—72)

My invention relates to the inscription of a series of concentric circles, four being the most convenient number for my purpose, on the diaphragm in the reticule of the telescope having a sufficiently large field of view of such surveyors' instruments as are equipped with such diaphragms in their reticles, and the inscribing of graduations and figures denoting time intervals thereon, which said diaphragms may be of glass or other suitable substance, and which, as is well known, are inserted in the telescope of surveying instruments; or in the case of surveying instruments whose telescopes have the proper field of view, but are not equipped with diaphragms in their reticles, the inscription of said concentric circles on a diaphragm together with the graduations and figures denoting time intervals, especially constructed for use with them; the said concentric circles with their attendant graduations and figures denoting time intervals being used in conjunction with the formulae herein set forth by which observations on Polaris for azimuth may be made with a minimum of calculation without any timepiece except an ordinary watch set to keep civil time.

I attain these objects by the artifices and formulae illustrated in the accompanying drawing, in which:

Figure 1 shews a typical reticule of a surveyor's transit equipped with a glass diaphragm on which have been inscribed, in addition to the customary vertical and horizontal lines, the series of concentric circles, which circles constitute the major part of my invention.

Figure 2 shews, on an enlarged scale the said concentric circles, and graduations and figures denoting time intervals.

Figure 3 shews in their proper places, and designates, the geometrical elements which enter into the derivation of the formulae.

Figures 4 and 5 shew the positions of Polaris in the various quadrants.

Similar letters and figures refer to similar parts throughout the drawing.

Referring to the drawing:—

1 represents the metal ring of the reticule with the four adjusting screws, 2 represents the diaphragm fastened to the ring of the reticule. 3 and 4 represent, respectively, the vertical and horizontal lines inscribed on the diaphragm. But as these features do not constitute my invention, no further description of them is necessary. 5 represents the series of circles having for a common centre the point of intersection of the vertical and horizontal lines 3 and 4. (In Figure 1

these concentric circles are not shewn separately, but are represented by one heavy black circle.) In Figure 2 which is drawn to an enlarged scale, 5 represents the four concentric circles with radii as follows:— $f \times \tan(\alpha + 1'30'')$, $f \times \tan(\alpha + 0'30'')$, $f \times \tan(\alpha - 0'30'')$ and $f \times \tan(\alpha - 1'30'')$, where f is the focal length of the object glass of the transit instrument, and α , to the nearest one-half minute, the average co-declination of Polaris for a certain ten-year period. For the decade ending December 31st, A. D. 1939, α equals one degree, two minutes, and thirty seconds ($1^\circ 02' 30''$). For subsequent decades new diaphragms will have to be prepared in accordance with my invention.

The marks 6 represent divisions of astronomical time, the space between the smallest divisions representing ten minutes.

The figures 7^m, 6^m, etc. on the outside of the outermost circle represent certain intervals of civil time calculated from the formula:

$$(dh)'' = \cot h \times \cot \alpha \times 30''$$

where h represents the hour-angle of Polaris reckoned east or west from the upper or lower culmination, according to the quadrant in which Polaris happens to be situated. (dh) seconds of arc are then converted into seconds of civil time by multiplying by

$$\frac{23.9345}{24} \times \frac{1}{15}.$$

Referring to Figure 3, (dh)'' represents the seconds of arc that Polaris must travel in order that

$$\frac{\delta_1''}{\delta_2''} \text{ may be equal to } \frac{m_1''}{m_2''},$$

where δ_1'' , δ_2'' are the seconds of arc by which the co-declination of Polaris exceeds or falls short of the arcual radii of the adjacent circles of the series between which said co-declination lies; and where m_1'' , m_2'' are the angles which true north makes with the two directions of the telescope conditioned by the two circles in question. This formula is approximate only, but gives values within two seconds of arc when h is not less than fifteen degrees, and when the latitude of the place of observation is not greater than seventy-five degrees. This formula constitutes a prominent feature of my invention. Its derivation from Figure 3 is given below:—

Derivation of formulae

Referring to Figure 3, ρ represents the polar distance of Polaris; $\rho + \delta_1''$, and $\rho - \delta_2''$, the

arcual radii of the critical circles; h the hour angle of Polaris; m_1'' , m_2'' angular deviations due to δ_1'' and δ_2'' measured on the small circle in the heavens with the zenith as centre. These 5 angular deviations measured on the horizon would be $m_1'' \times \sec L$ and $m_2'' \times \sec L$ where L is the latitude of the place of observation. O represents the celestial pole and C the upper culmination. We find a formula for $(dh)''$ in order 10 that the ratio

$$\frac{\delta_1''}{\delta_2''}$$

may become approximately equal to the ratio

$$15 \quad \frac{m_1''}{m_2''}.$$

At the outset we make certain assumptions: (a) P is the average co-declination of Polaris for the ten-year period; (b) m_1 and m_2 are considered 20 arcs of great circles. While these assumptions lead to small errors, it may be shewn that these, in the most unfavorable cases, when the hour angle of Polaris is fifteen degrees and the latitude seventy-five degrees, do not produce any 25 appreciable error in the azimuth.

We are now ready to deduce our formula:—

$$\cos(\rho + \delta_1) = \cos \rho \cos m_1 - \sin \rho \sin m_1 \cos \delta_1$$

$$\cos(\rho - \delta_2) = \cos \rho \cos m_2 + \sin \rho \sin m_2 \cos \delta_2$$

$$30 \quad \therefore (\cos \rho \cos \delta_1 - \sin \rho \sin \delta_1) \sin m_2 = \\ \cos \rho \cos m_1 \sin m_2 - \sin \rho \sin m_1 \sin m_2 \cos \delta_2$$

and

$$(\cos \rho \cos \delta_2 + \sin \rho \sin \delta_2) \sin m_1 = \\ \cos \rho \cos m_2 \sin m_1 + \sin \rho \sin m_2 \sin m_1 \cos \delta_1$$

$$35 \quad \therefore \cos \rho [\cos \delta_1 \sin m_2 + \cos \delta_2 \sin m_1] + \sin \rho [\sin m_1 \sin \delta_2 - \sin m_2 \sin \delta_1] = \\ \cos \rho \left[m_1 + m_2 - \frac{(m_1 + m_2)^3}{6} \right] + \sin \rho \sin m_1 \sin m_2 \times 2 \sin \frac{\delta_1 + \delta_2}{2} \sin \frac{\delta_1 - \delta_2}{2}$$

40 But since we want the condition under which

$$\frac{\delta_1}{\delta_2} \text{ equals } \frac{m_1}{m_2},$$

or, since all the angles are small, under which

$$45 \quad \frac{\sin \delta_1}{\sin \delta_2} \text{ equals } \frac{\sin m_1}{\sin m_2},$$

we can drop out the term

$$\sin \rho [\sin m_1 \sin \delta_2 - \sin m_2 \sin \delta_1]$$

50 from the last equation. Doing this, expanding, and using the relation

$$\frac{\delta_1}{\delta_2} \text{ equals } \frac{m_1}{m_2},$$

55 we have:

$$\cos \rho \left[m_1 + m_2 - \frac{m_1^3}{6} - \frac{m_2^3}{6} - \frac{m_1 m_2}{2} \right] \times \frac{(\delta_1 + \delta_2)^2}{m_1 + m_2} = \cos \rho \left[m_1 + m_2 - \frac{(m_1 + m_2)^3}{6} \right] +$$

$$\sin \rho \sin m_1 \sin m_2 \times 2 \cos \left(h + \frac{dh}{2} \right) \sin \frac{dh}{2}$$

60

We can put:—

$$\frac{\delta_1}{m_1} \text{ equals } \frac{\delta_2}{m_2} = \frac{\delta_1 + \delta_2}{m_1 + m_2} = \sin h,$$

65 approximately. Hence after easy deductions

$$\cot \rho \times \frac{\frac{\delta_1 + \delta_2}{m_1 + m_2} \times \frac{\cos^2 h}{\sin h}}{\cos \left(h + \frac{dh}{2} \right)} \times \left(1 + \frac{\delta_1^2 + \delta_2^2}{6 \sin^2 h} \right) = 2 \sin \frac{dh}{2}$$

70 or, approximately,

$$(dh)'' = \cot \rho \cot h \times 30'' \text{ (since } \delta_1 + \delta_2'' = 60'').$$

75 There are approximations used in this derivation, but these can never, even for h equals

fifteen degrees and L equals seventy-five degrees, give rise to an error greater than about two seconds in the azimuth. So that all the errors involved in the various approximations, if of the same sign, may cause a maximum error of two 80 seconds in azimuth.

As Polaris will be closest to the celestial pole in the year 2102, when its co-declination will be about twenty-seven minutes and thirty-seven seconds (27' 37''), there is no danger, for some time to come, of this method becoming useless. After the year 2102, Polaris will gradually recede from the pole until its co-declination will have become so great that no field of view of any surveyor's instrument, will, with one pointing, comprise the whole of its journey around the pole. 85

The following is the practical exposition of my invention:—

The surveyor will have to know the declination of Polaris for the day of the observation, hence he will have to be supplied with a Nautical Almanac, or ephemeris, or something equivalent. He must also be provided with a watch regulated to keep accurate civil time. This, assuming on his part a knowledge of the approximate longitude of his place of observation, will enable him to predict from information supplied in the almanac or ephemeris what the approximate hour-angle of Polaris will be at any given local civil time. It is also necessary for the 100 surveyor to know the latitude of the place of observation as accurately as the degree of precision desired in the determination of the azimuth warrants. This, in surveyed territory, 105

110

every surveyor will know. In unsurveyed territory the usual observations of Polaris at upper or lower culmination, or both, will supply the surveyor with the desired information.

If Polaris is very near the upper or lower culmination—say within 15° of arc, or one hour 115 in time—the method fails. At all other times, whenever the usual methods of observation on Polaris are applicable, the method herein outlined is also applicable. The surveyor then proceeds as follows:—

To find the azimuth of a given line

First, knowing the arcual radii of the series of circles, he knows the two circles whose arcual radii are, one, the next greater, and the other, 120

125

130

the next less, than the co-declination of Polaris. Let these two circles be called the outer and inner "critical circles". (If the polar distance of Polaris happens to be exactly the radius of one of these circles, the process is so much simplified.) Set the alidade to zero and clamp. Sight telescope on reference object on the ground. Clamp lower limb. Lay off on vertical circle latitude + refraction of the pole, (if great accuracy is desired we make a correction in refraction for the situation of Polaris above or below the pole, which can be obtained graphically, as we know beforehand fairly accurately where Polaris is situated.) Loosen the upper clamp. Turn alidade until Polaris is in the proper quadrant be- 135

135

140

145

150

tween the critical circles. Then clamp alidade and with the upper slow motion screw move the alidade until the outer "critical circle" bisects the image of Polaris, if the said image of Polaris occupies either of the two positions indicated in Figure 4; or until the inner "critical circle" bisects the image of Polaris, if the said image of Polaris occupies either of the two positions indicated in Figure 5. Read the horizontal circle; if Polaris is seen opposite the mark or graduation, 5^m, Figure 2, then wait five minutes. At the expiration of this time interval, move the alidade by the upper slow motion screw until the image of Polaris is bisected by the inner "critical circle", as indicated by the positions of the image of Polaris in Figure 4; or until the image of Polaris is bisected by the outer "critical circle", as indicated by the positions of the image of Polaris in Figure 5. Read the horizontal circle. Then if "a" and "b" are the horizontal circle readings corresponding to the positions of Polaris on the outer and inner "critical circles", as in Figure 4; or to the position of Polaris on the outer and inner "critical circles", as in Figure 5; and if δ_1'' and δ_2'' are the differences between the co-declination of Polaris and the arcual radii of the corresponding critical circles, then the azimuth of the reference line equals:

$$30 \quad a + (a-b) \times \frac{\delta_1''}{\delta_1'' + \delta_2''} = a + (a-b) \times \frac{\delta_1''}{60},$$

if $\delta_1'' + \delta_2'' = 60''$ exactly. (Due regard being had to the signs of the quadrants involved.)

35 Now we reverse, in the usual manner to eliminate instrumental errors, and take the mean of the two determinations.

For the positions of Polaris between the marks corresponding to two time-intervals, the proper time-interval to use can be estimated to the nearest ten seconds, which is sufficiently accurate.

To lay off on the ground a line having given a certain azimuth

45 Set alidade to zero. Lay off on the vertical circle the latitude plus refraction of Polaris, as before. Turn the instrument by its lower slow motion screw so that the image of Polaris is bisected by the outer "critical circle", if the image of Polaris occupies either of the two positions indicated in Figure 4; or until the inner "critical circle" bisects the said image of Polaris if it occu-

pies either of the two positions indicated in Figure 5. If the image of Polaris is seen opposite the mark or graduation, say 4^m, Figure 2, then wait four minutes; and at the expiration of this time interval move the alidade by the upper slow motion until Polaris appears on the inner "critical circle", being bisected thereby, as indicated by the positions of the image of Polaris in Figure 4; or until the image of Polaris is bisected by the outer "critical circle", as indicated by the positions of the image of Polaris in Figure 5. Read horizontal circle of the instrument. Proportion as before, and by the upper slow motion make the horizontal circle read the corrected angle; the line is marked off on the ground in the usual manner. Reverse and repeat the process, as above outlined, to eliminate instrumental errors. Mark off on the ground the line corresponding to the reverse operations. Take the mean of the two lines so determined for the final line.

It is of course obvious that the reversing process here referred to applies only to the customary operations familiar to all surveyors and not to the "critical circles".

The rules referred to above, relating to the positions of Polaris in the various quadrants, and embodied in Figures 4 and 5, are essentially the same for both erecting and inverting eye-pieces in the telescopes of surveyors' instruments; and a corresponding rule for diagonal eye-pieces can 100 easily be evolved.

I am aware that prior to my invention diaphragms, made of glass or other suitable substance have been used in the reticules of surveyors' instruments, and that the ordinary vertical and horizontal cross lines have been ruled thereon. I therefore do not claim such a device; nor do I claim any means whereby lines, whether circular or curved may be ruled on glass or other suitable substance, which also applies to the 115 graduations, or figures, or any combination thereof broadly; but:

I claim:—

On a diaphragm to be inserted in the reticule of a surveyor's instrument, or transit theodolite, 120 the inscription of a series of concentric circles having radii determined in accordance with the formulae as set forth in the annexed specification, said circles having the graduations denoting time intervals for use in conjunction with the said 125 concentric circles, substantially as set forth.

STEPHAN GUTTORMSSON.
